UNITED STATES PATENT OFFICE.

WILLIAM F. M. HAWE, OF PITTSBURGH, PENNSYLVANIA, ASSIGNOR TO THE MACBETH-EVANS GLASS COMPANY, OF PITTSBURGH, PENNSYLVANIA, A CORPORATION OF PENNSYLVANIA.

DESIGN FOR A LAMP-GLOBE.

48,893.

Specification for Design.

Patented Apr. 18, 1916.

Application filed February 9, 1916. Serial No. 78,020. Term of patent 14 years.

To all whom it may concern:

Be it known that I, WILLIAM F. M. HAWE, a citizen of the United States, residing at Pittsburgh, in the State of Pennsylvania, have invented a certain new, original, and ornamental Design for a Lamp-Globe, as shown in the accompanying drawing, which is a side elevation exhibiting my design.

I claim:

The ornamental design for a lamp globe as shown.

WILLIAM F. M. HAWE.
